(No Model.)

J. S. SAMMONS.

COPYING PRESS.

No. 277,946.

Patented May 22, 1883.

UNITED STATES PATENT OFFICE.

JACOB S. SAMMONS, OF NEW YORK, N. Y., ASSIGNOR TO THE UNITED STATES PNEUMATIC COPYING PRESS COMPANY, OF SAME PLACE.

COPYING-PRESS.

SPECIFICATION forming part of Letters Patent No. 277,946, dated May 22, 1883.

Application filed June 15, 1882. (No model.)

To all whom it may concern:

Be it known that I, JACOB S. SAMMONS, a citizen of the United States, residing in the city of New York, county of New York, and State of New York, have invented certain new and useful Improvements in Copying-Presses, fully described and represented in the following specification and the accompanying drawings, forming a part of the same.

10 In said drawings, Figure 1 illustrates a longitudinal sectional elevation, and Fig. 2 a transverse sectional elevation, of a copying-press embodying my improvements. Fig. 3 is a detail view, showing the structure of the valves. 15 The present invention relates to improvements effected in copying-presses of the general structure of that shown in Letters Patent No. 235,966, granted to me December 28, 1880—that is, such copying-presses as are provided 20 with a platen that is moved by air or fluid pressure to produce the copying operation in a book confined between such platen and a bed.

The invention consists in an improved structure of bellows and its mountings; in a metal strengthening plate and rib applied, respectively, to the wooden top and bottom plates, whereby their structure is made stiff and strong enough to resist warping or straining, and thus 30 provide for a perfect operation of the pressing-platen; and in a peculiar construction of valve, as well as various combinations of parts, all particularly hereinafter described and claimed.

In its general structure the press shown 35 herein as embracing these improvements does not differ from that shown in said patent. Thus it consists of a bed-plate, A, and a top plate, B, connected together, preferably at the ends, by supporting-plates, through which said bed and top plates are rigidly held a suitable distance apart to accommodate a platen, C, and its air-bag D, and to permit the introduction and removal of a copying-book between said platen and the bed-plate, which supporting end plates, while they may be a single one at each end and permanently attached in most cases, are by preference made into two members, as 34, one of each attached to the top and bed plates, and provided with means, as 50 clamping-plates 7, for adjustment, so that more or less working-space may be provided be-

tween the bed-plate and platen, as circumstances may require. The platen C is provided with springs 5 to raise it, and is depressed by means of an air-bag, D, that has 55 an induction-port, H, communicating with a pump, E, and with an eduction-port, I, that communicates with the atmosphere.

In the present structure many improvements in the details are effected, by which the perfect operation of the structure is obtained.

To prevent the base or bed plate A from being twisted or distorted out of level by reason of the strain to which it is subjected, it is constructed in two pieces, 11 12, fitted to a longitudinal strengthening-rib, 13, which pieces 11 12 and rib 13 at their ends are embraced and securely held by the flanges 8 9 of the plate 4. The base or bed plate A, thus constructed, is not liable to warp laterally, and is given great 65 longitudinal stiffness, its level condition being thus maintained.

The improvements effected in the pump or air-forcing apparatus will best be understood by a description of its whole structure and 70 mounting. Instead of mounting its bellows in a wooden seat, as in said patent, I provide for its support a metal plate, F, of such dimensions as to receive the base of the bellows and provide for the induction and eduction ports 75 H I and their valves. This plate F is, moreover, extended longitudinally to nearly the extent of the top plate, B, whereby it further performs the function of imparting longitudinal and lateral stiffness to said top plate, thus 80 preventing undue straining or warping that member, which is preferably mainly constructed of wood. This plate is secured upon the under side of the top plate, B, by screws or other simple fastenings, and thus covers recesses 85 cut through the said platen to secure the bellows and the eduction-valve. The bellows 20 is constructed in cup form, thus slightly tapering upward. Its lower edge is turned outward and its upper edge inward to form flanges 90 95 whereby it may be secured. The lower flange is held snugly in place upon the plate F by means of a retaining-ring, 14, the lower edge of which has one or more projections or continuous ridges, that nip the fabric of which the bellows is composed and indent it as the ring is forced downward by its attaching-screws,

that enter and thus clamp it to said plate F. By the elastic nature of the fabric of the bellows or by an elastic packing, ring 15 may be depended upon to form an air-tight joint attaching the bottom of the bellows to the plate F. The upper flange of the bellows is secured to a head-plate, 16, by a flanged annulus, 17, between which said flange is tightly embraced, as said plate and annulus are secured together by screws or similar fastenings. This head-plate is provided with a central bearing for the handle or operating-lever L, and at proper points with feeding-valves 18, through which the air is admitted to the bellows.

As it is requisite that the bellows should lap or fold together with regularity and precision when compressed, each folding-point is provided with a wire hoop or band, 6, the function of which is not only to impart circumferential strength, and thus prevent lateral distortion and unusual wear, but to compel each fold to move with vertical regularity as the bellows is operated by the lever L. To cause the ascent of the bellows it is provided interiorly with a circular spring that encircles a hub, 19, at the bottom and embraces the annulus 17 at the top. When the bellows is collapsed the bends of this spring are laid snugly around said hub and the folds of the bellows are superposed in a regular pile.

The air-bag D is a long flat sack-like structure supported between the platen C and the top plate, B. It is connected with the bellows by its induction-port H, and to the top plate, B, by its eduction-port I, both of which are valves of the same though peculiar construction, especially adapting them to an apparatus of this nature where the slightest escape of air should be prevented. (See Fig. 3.) They each consist of a housing formed by a body, 30, flanged to fit a recessed seat in the plate F, into which body a bottom member, 31, and a top member, 32, are secured by fastening screw-threads. The flange of the body 30 and a similar one upon the member 31 are provided to embrace the material of the sack, and thus form an air-tight joint. The member 31 is provided with air-passages a, and with a central slot, forming a guide for the stem t of the valve

e, and the member 32 is provided not only 50 with an air-passage, o, but with a seat, s, for the valve e, which seat is formed by a projecting neck having a sharp edge. The valve e has a cup-shaped head, in which is held a rubber or other soft cushion that will be indented by contact under pressure with the sharp-edged neck or valve-seat s. This valve is carried upon a light helical spring, i, which has power sufficient to raise the valve to its seat, and yet permit such valve to be readily depressed by the air forced from the bellows in the case of the port H and by the pressure of the spring-seated rod n in the case of the port I, which rod is provided with a cap, O, and returning-spring, and acts to open the education-port I when the air is to be discharged from the apparatus, which is accomplished by pressure of the finger of the operator. The rod n is seated in a portion of the housing X, which protects the bellows 20 and affords a 70 pivotal bearing for the handle or lever L.

What is claimed is—

1. The combination, with the top plate, B, recessed to receive the bellows, of the metal plate F, substantially as described.

2. The combination, with the bed-plate A, of the longitudinal strengthening-rib 13, substantially as described.

3. The combination, with the body 30, having flanged bottom, screw-threaded flanged bottom member, 31, having air-passages, and carrying puppet-valve te, with cushioned head, and screw-threaded top member, 32, having air-passage and neck-like valve-seat S, substantially as described.

4. The combination, with the air-bag D and the plate F, having a flanged seat, of the flanged body 30 and flanged bottom member, 31, of the air-valves, whereby a rigid seat and air-tight joint are effected, substantially as described.

In testimony whereof I have hereunto set my hand in the presence of two subscribing witnesses.

JACOB S. SAMMONS.
